UNITED STATES PATENT OFFICE.

HOWARD ADDISON JOHNSTON, OF TORONTO, ONTARIO, CANADA.

AUTOMATIC DOOR-OPENING MECHANISM.

Application filed October 1, 1925, Serial No. 59,911. Renewed May 11, 1928.

This invention relates to means whereby a door or gate may be automatically caused to open or close by the passage of a vehicle over a suitable trip device.

5 My object is to construct a simple and effective device of this nature which is operable by each of two successive operations of the trip and non-operable by either of two following successive operations of the trip, 10 whereby the device will be operated to open the doors when the leading wheels of a four-wheeled vehicle pass over the trip and will not thereafter be automatically operated to close the doors until the same wheels again 15 pass over it in the reverse direction which will not usually occur until the rear wheels have passed over the trip in both directions; to arrange the apparatus so that the doors may be manually controlled without upsetting the trip sequence aforesaid; to arrange 20 the apparatus so that the power for effecting the movements of the door is obtained from a shaft which is actuated by any suitable motive power in one direction; to provide 25 means for disconnecting the doors from the power operating connections so that they may be manually operated; to provide simple weight actuated means for supplying the motive power; and to provide means whereby the vehicle itself may be employed to 30 wind up the weight.

I attain my object by means of the constructions hereinafter described and illustrated in the accompanying drawings in 35 which

Fig. 1 is a plan view, partly broken away and partly in section, showing my invention applied to garage double doors;

Fig. 2 a side elevation of the same, partly 40 in section and partly broken away;

Fig. 3 a plan view of the trip and escape mechanism in the locked position;

Fig. 4 a similar view of the same parts in the released position;

45 Fig. 5 a sectional detail of the connection between one of the doors and a connecting rod for moving the same;

Fig. 6 a section of the mechanism for putting the device into operation by one of the 50 wheels of the vehicle, and

Fig. 7 a perspective detail of the toggle levers for permitting a door to be opened and closed independently of the door opening mechanism.

In the drawings like numerals of reference 55 indicate corresponding parts in the different figures.

1 is the representation in outline of a garage provided with hinged double doors 2. Each door has pivotally connected thereto 60 one end of a connecting rod 3, the other end of which is pivotally connected with a cross-head 4 longitudinally movable in a guide 5 suitably supported overhead in the garage. This cross head is adapted to be actuated by 65 a connecting rod 6 pivotally connected to one end of the crosshead and at the other end to a crank arm 7 secured to a shaft 8 suitably journalled on the guide 5. The crank arm is so proportioned that one revolution 70 of the shaft will either open or close the doors and return them to their original position. Suitable motive power is applied to the shaft tending to rotate it to operate the doors as described. I show weight-operated 75 mechanism for this purpose, though it will be understood, of course, that springs or other motive power might be substituted. On the shaft 8 is journalled a drum 9 on which is wound the cord 10, which is led over suitable guide pulleys 11 and has secured to its free end the weight 12. The drum carries a spring actuated dog 13 adapted to engage a ratchet wheel 14 secured to the shaft 8. On the drum is also wound 80 a cord 15 which is carried round suitable guide pulleys 16 and which may be operated to wind up the weight 12 after it has run down. This cord might be operated by hand, or, as shown, means may be provided 85 whereby the power of the motor vehicle using the garage may be used for that purpose. I show a guide 17 secured to the floor of the garage on which is mounted for longitudinal movement a slide 18. On this slide is pivoted a dog 19 adapted to be engaged by the front axle of the motor vehicle. This dog normally tends to remain in the position shown in Fig. 2 in which it is engageable by the axle. The tail 20 of the dog is adapted 95 to engage a stationary stop 21 when the cord 15 has been sufficiently drawn up to fully wind up the weight whereby the dog is rocked and released from the axle leaving the vehicle free to move out.

100 Releasable means are provided for holding the shaft 8 from rotation and means are also provided for releasing the stop mech-

anism from either a point adjacent the garage or remote therefrom. I prefer to employ means operable by the passage of the wheels of the vehicle for automatically opening and closing the doors from a remote point and manually operable means for operating the doors from a position adjacent the garage, though, of course, manually operable means may be employed at both locations.

10 The releasable stop mechanism preferably comprises an escapement lever 22 of known type, the pallets 23 of which are adapted to engage in a known manner the teeth 24 of the escapement wheel 25 secured to the shaft 8. By rocking the escapement lever, one tooth at a time is allowed to escape, thus permitting a half revolution of the shaft 8 for each oscillation of the escapement lever. To the escapement lever is connected 15 one end of a cord 26, which is led round suitable guide pulleys 27 and is connected to an operating handle 28 suitably positioned adjacent the doors, though, of course, the handle may be located, if desired, in a 20 position convenient for distant operation.

25 To automatically operate the escapement lever, I provide the mechanism which I will now describe. To better enable this mechanism and its operation to be understood, it is desirable at this point to set out the 30 cycle of operations which will usually be necessary in taking a motor vehicle into and out of the garage. Any trip device operable by the wheels of the vehicle will be passed 35 over twice by the wheels of the car as the car goes into the garage, once by a front wheel and once by a rear wheel, and twice as it goes out of the garage. The mechanism will therefore be arranged so that when one 40 of the front wheels of the car approaches the garage, it passes over the automatic trip device and operates the escapement lever to cause the opening of the doors. As the rear wheel passes over the trip device, it 45 must not trip the device, otherwise the doors would again close. When the car is in the garage, the mechanism will be operated by hand to close the doors and also tripped manually to open the doors when the car is 50 to pass out. Thereafter one of the rear wheels of the vehicle will pass over the trip device and must not operate the same, whereas when one of the front wheels passes over 55 the device, the escapement lever must be operated to cause the automatic closing of the doors.

60 To obtain the desired sequence of operation, I provide the trip mechanism with what may be termed counting mechanism, whereby the actual tripping means is conditioned to operate the escapement lever at any desired point or points in a sequence of movements of the trip. This mechanism is shown in Figs. 3 and 4 of the drawings. 29 65 is a count wheel, which is pivoted on a rock

70 arm 30 fulcrumed on the escapement lever 22. As in the present case it is desired that the trip lock shall operate the escapement lever twice in succession and then miss twice, the count wheel is provided with two projections 31 at right angles to one another, though it is evident, of course, that these need not be entirely separate projections, as the arc between them may be filled out and the same result attained.

75 Formed on or connected with the count wheel is the four toothed ratchet wheel 32, which is adapted to be engaged by a spring actuated dog 33 pivoted on a stationary part. From the construction described it follows 80 that as the rock arm 30 is oscillated, the count wheel is given a stepwise rotation through an arc of 90° at a time, and thus the projections 31 are successively brought in a position to engage the escapement lever and thereafter for two movements of the rock arm no movement is imparted to the escapement lever. The desired sequence of 85 operations is thus secured. It is evident, of course, that the count wheel and its ratchet 90 may be arranged to give any suitable sequence.

95 The rock arm 30 is connected by means of a cord 34 led round suitable guide pulleys 35 to the wheel operable device hereinbefore referred to. This comprises a base 36 on which is suitably journalled a crank 37 formed by a blade 37^a secured to a shaft. To one end of this shaft is secured a double 100 cam 38 which engages a spring pressed crosshead 39 suitably connected with the cord 34. The crosshead is slidably mounted in an enclosed guideway formed on or secured to the base 36. The parts are normally positioned as shown in Fig. 6 with the 105 blade 37^a upright due to the spring pressed crosshead engaging both cams 38. Riding over the blade rocks it and thus the cams 38, either one of which moves the crosshead to cause a pull on the cord 34. The 110 cord will preferably be provided with any known means for taking up slack.

115 It is desirable that at least one of the doors shall be disconnectable from the operating mechanism so that it may be opened and closed by hand. For this purpose I connect one of the rods 3 to the free end of the toggle levers 47 which are pivotally connected with one another and to a bracket 40 secured to one of the doors. The lever 47^a 120 to which the rod 3 is connected is longer than the other toggle lever and is adapted to be locked to the door by means of a wedge shaped projection 48 formed on or secured to the bracket 40. To release the lever 47^a I provide the bracket with a socket 41 in which a lift rod 43 is slidably mounted. When the lift rod is pushed upwardly it will 125 disengage the lever 47^a from the keeper or projection 48 thus leaving the door free 130

to be moved independent of the connecting rod. When the door is closed the lever 47^a will slide over the wedge on the projection 48 and drop into engagement with the latter. Should the lever 47^a be disconnected from its projection 48, the operating mechanism when operated to open the door will cause the lever to engage the projection and thus automatically re-establish the connection between the operating mechanism and the door. Any suitable means may be provided to operate the lift rod but I prefer to employ, however, a cam 44 secured on one end of a spindle 45 journaled in the door and provided with a knob 46 whereby it may be operated.

What I claim is:—

1. Door operating mechanism comprising a shaft; a connecting rod adapted to be connected to a door; means whereby the rotation of the shaft reciprocates the connecting rod to open and close the door; means tending to rotate the shaft; an escapement lever adapted, each time it is operated, to permit the shaft to move one-half revolution; and means for actuating the escapement from a convenient point including a counting device whereby the escapement is operated only at predetermined intervals in a predetermined cycle of operations of the escapement actuating means.

2. Door operating mechanism comprising a shaft; a connecting rod adapted to be connected to a door; means whereby the rotation of the shaft reciprocates the connecting rod to open and close the door; means tending to rotate the shaft; an escapement lever adapted, each time it is operated, to permit the shaft to move one-half revolution; means for actuating the escapement from a convenient point including a counting device whereby the escapement is operated only at predetermined intervals in a predetermined cycle of operations of the escapement actuating means; and means for actuating the escapement independent of the counting device.

3. Door operating mechanism comprising a shaft; means tending to rotate the shaft; means actuated from the shaft for opening or closing a door; an escapement lever adapted, each time it is operated, to permit the shaft to move one-half revolution; means for actuating the escapement from a convenient point including a rock arm; a rotary contact member mounted on the arm; a four toothed ratchet wheel on the contact member; a pawl pivoted on a stationary part and adapted to pick the ratchet wheel as the rock arm is oscillated; two contact surfaces on the contact member corresponding in position to two adjacent ratchet teeth; and an arm on the escapement lever engageable by said surfaces to rock the escapement, whereby four consecutive oscillations of the

rock arm result in only two consecutive actuations of the escapement.

4. Door operating mechanism comprising a shaft; a drum loose on said shaft; a pawl and ratchet driving connection between the drum and shaft; a cord wound on the drum and provided with means tending to rotate the shaft; means actuated from the shaft for opening or closing a door; a second cord wound on the drum; a slide mounted to reciprocate horizontally; guide rollers round which the second cord is led and connected to the slide; a pivoted dog on the slide adapted to be engaged by part of a vehicle; and a stationary trip adapted to be engaged by the dog to release it from the vehicle after a predetermined movement of the dog, and the attached cord, has been effected.

5. Door operating mechanism comprising a shaft; means tending to rotate the shaft in one direction; a crank arm on said shaft; a guide; a cross head reciprocable on said guide; a connecting rod pivotally connected to the crank arm and the cross head; connecting rods pivotally connected with doors and with the cross head, whereby the rotation of the shaft reciprocates the connecting rods to open and close the doors; an escapement lever adapted, each time it is operated, to permit the shaft to move one half revolution; and means for actuating the escapement from a convenient point; and means for automatically re-winding the shaft rotating mechanism by the vehicle.

6. Door operating mechanism comprising a shaft; a slide; means whereby the shaft actuates the slide; a connecting rod; pivotally connected to the slide; a door to which the connecting rod is pivotally connected; means including linkage for permitting lost motion in the connections whereby the door may be swung independently of the connecting rod; a releasable locking device including a part extending through the door to the outside whereby the connecting rod is normally held in operative connection with the door but may be released at will; and means for actuating the shaft.

7. Door operating mechanism comprising a shaft; means tending to rotate the shaft; a slide; means whereby the shaft actuates the slide; a connecting rod pivotally connected to the slide; a door to which the connecting rod is pivotally connected; escapement mechanism adapted to control the rotation of the shaft; a guide; a slide movable along the guide and adapted for engagement by a vehicle; and connections whereby the movement of the slide will re-wind the shaft rotating means.

8. Door operating mechanism comprising a shaft; a connecting rod operable by the shaft; a door; toggle levers comprising a short and a comparatively long lever pivotally connected with one another, the free end

of the long lever being pivotally connected with the connecting rod and the free end of the short lever being pivotally connected with the door; a keeper carried by the door for releasably locking the long lever in operative connection with the door; and means for actuating the shaft.

9. Door operating mechanism comprising a shaft; a connecting rod operable by the 10 shaft; a door; toggle levers comprising a short and a comparatively long lever pivotally connected with one another, the free end of the long lever being pivotally connected with the connecting rod and the 15 free end of the short lever being pivotally connected with the door; a keeper carried by the door for releasably locking the long lever in operative connection with the door; manually operable means adapted to move 20 the long lever free of the keeper; and means for actuating the shaft, the long lever being adapted to engage the keeper to re-establish its operative connection with the door when

the lever or door is sufficiently moved relative to one another.

10. Door operating mechanism comprising a shaft; a slide; means whereby the shaft actuates the slide; means tending to rotate the shaft; a connecting rod pivotally connected to the slide; a door to which the connecting rod is pivotally connected; escapement mechanism adapted to control the rotation of the shaft; a guide; a slide movable along the guide; a dog pivoted on the slide and provided with a tail, the dog being adapted for engagement with a vehicle; connections whereby the movement of the slide and dog will re-wind the shaft; rotating means and a stationary trip adapted to be engaged by the tail to release the dog from the vehicle after a predetermined movement of the dog, slide and connections has been effected.

Signed at Toronto this 25th day of September, 1925.

HOWARD ADDISON JOHNSTON.
